UNITED STATES PATENT OFFICE.

JOHN J. RALYA, OF ANDERSON, INDIANA.

SAW.

SPECIFICATION forming part of Letters Patent No. 364,131, dated May 31, 1887.

Application filed July 19, 1886. Serial No. 208,440. (Model.)

To all whom it may concern:

Be it known that I, JOHN J. RALYA, of Anderson, in the county of Madison and State of Indiana, have invented certain new and useful Improvements in Saw-Teeth; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to a special and novel construction of saw-teeth and of saws provided with the same, as will hereinafter fully appear, and having for its objects more efficient and rapid cutting, the prevention of bending or crumbling away of the extreme end of the cutting-teeth, the effecting of a better clearance, and the saving of much time and expense incident to the gumming of saws, and other advantages hereinafter named.

In the drawings, Figure 1 shows in plan view sufficient of a crosscut-saw to illustrate my invention; Fig. 2, a central lengthwise section, enlarged, through one of the cutting-teeth; Fig. 3, an edge view of one of the cutting-teeth; Fig. 4, an edge view of one of the clearing or drag teeth.

My invention is applicable for saws of other kinds as well as for cross-cut ones.

A is the body or plate of the saw; B B', the cutting-teeth; C C, the clearing or drag teeth; E E, the large wide deep spaces between the cutting-teeth and the drag-teeth; F, the shallow and narrow spaces between the cutting-teeth B B'.

I will first describe the peculiar construction of the cutting-teeth B B'. Each of them is made with a double bevel, or rather with two bevels, *g* *h*, the two bevels meeting at an obtuse angle, *i*, and the outer edge of the bevel *h* constituting the cutting-edge, and these two bevels meeting to form the point of each cutting-tooth. This double bevel, it is found in practice, affords, among others, the following advantages, namely: It allows of greater thickness, and consequently greater strength and durability, of the tooth than if made with the customary single bevel or chisel edge, because a single bevel would not permit that

thickness or swell or ridge near the cutting-edge, such as shown at *i*, and this thickness at that portion of the blade of the cutter gives sufficient rigidity to prevent the turning over or bending or crumbling away of the edge, and which would destroy its efficiency in action and soon render the saw useless. Another advantage due to this double bevel is as follows: When a bevel is single and straight, as in saws generally, it is not safe or practicable to extend it back far from the tip or edge of the teeth, because this reduces for too great a distance from such tip or edge the thickness of the metal, and renders it laterally yielding and flexible, and thus impairing the work and the strength and the wear of the teeth and of the saw; but by making the second bevel, *h*, which meets the plane of the metal at a greater or more obtuse angle than the bevel *g* would if projected, this latter bevel may be permitted to extend backward a much greater distance than could be done with a single straight bevel, because at no point in the line of this bevel *g* is the thickness of the blade or tooth less than is shown at *i*, and the tooth therefore is secure against any undue thinness, weakness, or liability to bend or to get out of good operative shape. This double bevel, furthermore, gives a clearance without affecting the extreme point of the tooth, and allows the teeth to sink into the wood or log more rapidly than with any other saw known to me. The general strength of all these teeth B B' is thus enhanced, and the saw is proportionately valuable in the manner, rapidity, and completeness of its work, in its lesser liability to damage, in its needing sharpening less frequently, and in its longer wear when in use.

The shallow and narrow spaces F between the cutting-teeth not only permit these teeth to be near to each other, and thus, being part of the same projection J of the blade, serving to support each other, but another great advantage results from this—namely, that the saw needs but little, if any, special gumming of the space F, because the very act of sharpening the cutters will, by reason of the requisite position of the edge of the file by the action of any other sharpening-instrument, at the same time gum or cut away the bottom line, *l*, of the space F, thus saving the time and labor usually re-

quired especially for gumming, besides avoiding the loss of time and the removal of the saw to take it to a gumming-machine, emery-wheel, or other gumming device.

5 Another feature of my improved saw relates to a provision of large ample space between the drag-teeth and each pair of cutting-teeth for the better clearing of the sawdust from the log, while at the same time bringing the right 10 and left cutting-teeth of each pair comparatively near to each other, with a small narrow space between them. This large broad deep space E is preferably made quadrangular, as shown, in a straight saw, and of a depth and 15 width, say, from four to five times as great as those of the narrow space F. This latter space, also, is preferably of rectangular shape, or nearly so, and each of these spaces F, as well as its two adjacent cutting-teeth, is made in 20 each of the projecting parts J of the plate, which is located between two of the large spaces E. The small space F thus but slightly affects the strength of the parts J, and the cutting-teeth thus practically support each other, 25 and their requisite stiffness is preserved as well as or better than when a single short cutting-tooth only is made, as customary; and in a saw of given length I get as many cutting-teeth as in ordinary saws, notwithstanding the fact that 30 so much of the length of the saw is taken for the broad spaces. The advancing cutter of one pair is preferably sharpened on the side opposite that of the advancing one of the next adjacent pair. It thus more freely enters the 35 kerf or cut as made by the last preceding cutting-tooth. I find that my saws stand stiffer and cut smoother and faster than any known to me.

Two drag-teeth, C C, are cut in the end of 40 each projection K, the two teeth being formed on a projection similar, but preferably somewhat narrower, than those in which the cutter-teeth are made. They are of uniform thickness with the saw-plate and formed by 45 two downwardly-inclined cuts meeting or nearly meeting at the center of the projection K. By not having these cuts meet at a positive acute angle at their bottom, there is an avoidance of liability to become clogged by 50 sawdust or bits of wood.

I find that with my invention, besides saw-

ing nearly twice as fast as usual, there is great saving in the expense of gumming, which is an important item, not only because of the cost of gumming and the gradual waste of the material of the saw, but also because of throwing the saw out of use while being gummed. 55

As already stated, the small space F needs no special gumming, the sharpening of the saw serving to deepen the space as needed. 60

The large space E is not likely to need gumming; but, if it should, it can be done by any inexperienced person, without removing the saw, by filing it away with the flat wide side of a file, and at but little waste of time and 65 without any expense.

I claim—

1. A saw-tooth made, as described, with a double-beveled point—that is, having the bevels *g* extending toward but not reaching to 70 the edge of the tooth and the other bevels, *h*, meeting said bevels at an obtuse angle and continued to form a cutting-edge on the tooth.

2. In a saw, the series of long projections J, each having at its extremity a pair of short 75 cutting-teeth, B B', with a small open space between them, and each tooth having its cutter double-beveled, as shown and described.

3. In a saw made with the series of pairs of cutters having small shallow spaces F between 80 the cutters of each pair, the cutters each having the double bevels, as described, and with the series of pairs of drag-teeth, the space between each drag-tooth and each pair of cutters being very broad and deep, substantially 85 as and for the purposes set forth.

4. In a crosscut-saw having the deep broad spaces E between the cutting-teeth and the drag-teeth and the narrow shallow spaces F between each pair of cutting-teeth, the double-beveled cutting-teeth B B', the teeth B' of adjacent pairs being beveled on one side or face and the other or more distant teeth, B, being beveled on the opposite side or face, and whereby the forward or advancing cutter of each 90 pair shall enter at one side of the kerf and the rear cutter of the next following pair shall enter at the same side.

JOHN J. RALYA.
